UNITED STATES PATENT OFFICE.

FRANK J. QUICK, OF ARLINGTON, RHODE ISLAND, ASSIGNOR OF FORTY PER CENT TO
MAX L. KRAMER, OF CRANSTON, RHODE ISLAND.

FLOWER HOLDER.

Application filed July 19, 1927. Serial No. 206,850.

This invention relates to certain new and useful improvements in flower holders and more particularly relates to a flower holder which is made of pottery.

5 The primary object of the invention is to provide a flower holder which has novel means for supporting the flowers in an upright position and which also has improved means for supplying water to the flower without interference from the latter, thereby to enable the water to be supplied both easily and quickly and without spilling or otherwise dropping same onto the surface on which the holder is supported.

10 Still further the invention aims to provide a holder of this type which can be easily and quickly and economically produced.

In the drawings:

Figure 1 is a vertical sectional view of the 20 invention and

Figure 2 is a section on line 2—2 of Figure 1.

In proceeding in accordance with the present invention, a base 1 is provided which is 25 in the form of a pan or dish having a flat bottom 1 to seat on a supporting surface and having a rim 2 which is outwardly curved at its top as indicated at 3. The body of the holder indicated at 4 is secured at its lower edge 30 to the bottom of the base 1 so that the latter provides a closure for the lower end of the body. The upper end of the body is flared outwardly as indicated at 5. A tubular head 6 is secured to and within the body 4 and is 35 of hollow construction having its upper end flared outwardly at 7 and its lower end similarly flared outwardly at 8. The lower end of the head 6 is provided with a series of spaced feet 9 which latter are secured to the body 4 so as to practically be integral therewith.

In manufacture, the parts are all made of pottery and the parts 1 and 4 and 6 are produced in integral formation. While the parts are in semi-green or uncured condition the legs 45 9 of part 6 are molded or worked into the interior of the body 4 at points below the top thereof, and upon curing of the body it will be seen that a completely integral structure results. It will be seen also that due to the 50 spacing of the legs 9, a series of inlets 10 are

provided, and in this regard it will be noted that as many of legs 9 may be employed as desired, three or more, the drawing showing four as an example.

In operation the stems of the flowers are 55 placed in the head 6 and entering the body 4 seat on the base 1. The flared rim 5 of the body 4, which is located considerably below the flowers, thus serves as an annular channel or reservoir, into which water may be 60 poured from a pitcher or a glass, and entering the inlets or spaces 10 fills the body 4 to any desired height. It will thus be noted that the body 4 can be filled with water without interference from the flowers and more- 65 over, can be as easily filled at any point throughout its entire circumference. If de- sired the level of the water in the body 4 can be disposed near the top of the latter and leaves or ferns or flower petals floated thereon. 70

The cup or dish-like formation of the base 1 also serves to collect any water which may possibly drip from the body 4 and also serves as an attractive and ornamental supporting 75 base for the entire structure.

Having thus described my invention what I claim as new and desire to secure by Letters Patent is:

A holder for cut flowers including a supporting base, a hollow body secured at its 80 bottom to the bottom of the base, and a head having spaced parts on its lower end secured to the interior of the body at points below the top of the body, the lower end portion of the head being laterally spaced from the upper end of the body to form an annular water- 85 receiving channel, the upper end of the head extending for a distance above the upper end of the body and forming an extension of the body whereby to support the heads of flower 90 stems at a distance above the top of the body thereby to enable water to be poured into the channel without interference from the flower stems, the head having each of its ends open so as to receive the cut flower stems there- 95 through and to enable the lower or cut ends of the stems to seat on the bottom of the base.

In testimony whereof I have signed my name to this specification.

FRANK J. QUICK.
